UNITED STATES PATENT OFFICE.

FRANK J. TONE, OF NIAGARA FALLS, NEW YORK, ASSIGNOR TO CARBORUNDUM COMPANY, OF NIAGARA FALLS, NEW YORK, A CORPORATION OF PENNSYLVANIA.

METHOD OF MAKING SILICON CARBID.

965,142.

Specification of Letters Patent. Patented July 19, 1910.

Application filed January 7, 1909. Serial No. 471,094.

To all whom it may concern:

Be it known that I, FRANK J. TONE, of Niagara Falls, county of Niagara, and State of New York, have invented a new and useful Improvement in Methods of Making Silicon Carbid, of which the following is a full, clear, and exact description, reference being had to the accompanying drawings, forming part of this specification, in which—

10 Figure 1 is a sectional side elevation showing one form of apparatus for carrying out my invention; and Fig. 2 is a similar view showing another form of apparatus therefor.

15 My invention relates to the production of silicon carbid, and is designed to reduce the number of furnaces necessary for a certain output and increase the output of single furnaces.

20 Under the present practice, a stationary electric furnace is employed consisting of a long rectangular receptacle with stationary electrodes at opposite ends, the charge of coke and sand being placed around a resistance core embedded therein. The current passes through the resistance core which is in contact with the electrodes in its end portion. The furnace is operated for a certain period varying from twenty-four to thirty-25 six hours, after which the current is cut off, the furnace cooled down, and the contents removed. It is then re-charged and the operation repeated. The period of cooling and re-charging occupies several days, and 30 consequently, a series of furnaces is necessary in order to keep one furnace in operation at all times. The output of a furnace is therefore comparatively small.

35 My invention is designed to afford a continuous process in which there is no cooling down or cessation of operation, the current being continuously supplied as are also the charge and core. The finished products are also removed in a substantially continuous 40 manner.

45 In the drawing, referring to the form of Fig. 1, I show a furnace of vertical type in which 1 and 2 are the upper and lower fixed electrodes held in any suitable manner. The 50 side walls of the furnace are formed of transversely divided refractory sections 3, secured to or having rack sections 4, engaging with pinions 5, 5, which may be operated in any suitable manner to give a continuous or intermittent downward move- 55

ment to the wall sections. The wall sections may be guided within any suitable supports or guides to hold the charge and core in place, and are added at the top and removed at the bottom in the downward movement. 60

The resistance conductor consists of granular core material 6, which is supplied at and around the upper electrode, and is surrounded by the charge mixture of carbon and silicious material 7, which is also supplied at the top. As the containing walls move downward, they carry with them the charge and resistance core. The rate of motion is so regulated that when the charge shall have reached the lower electrode, it 65 will have been converted into silicon carbid, the zone of carbid which is formed being of such diameter as will represent an economical rate of production. The lower electrode is preferably pointed or conical in 70 shape, so that the core material and finished product will be given an outward movement, and fed into a position where it may be readily removed from the furnace. 75

In Fig. 2, I show another horizontal type 80 of furnace for carrying out the process. In this case, the furnace proper consists of sections 8, having refractory floor and side walls abutting together to form a continuous channel-shaped furnace, which may be 85 open at each end and at the top. These sections are mounted upon carriers shown as trucks or wheels 9, and are given a longitudinal movement during the operation. The electrodes 10 and 11 are stationary and 90 depend from a fixed support 12. They extend through the upper portion of the charge 13, into the resistance core material 14. As the furnace sections travel endwise, the electrodes plow through the charge mixture and 95 maintain contact with the resistance core, the distance between the electrodes being constant at all times. Fresh mixture and fresh resistance core are supplied at the entrance end upon fresh sections of the furnace in advance of the first electrode, and after the reduced and finished charge passes the second electrode the products are removed and separated. The furnace sections are shown as traveling in the direction of 100 the arrow and in both drawings the hatched portion indicates the zone of silicon carbid product.

The advantages of my invention will be obvious to those skilled in the art. The 110

product of a single furnace is greatly increased, as the operation is substantially continuous; and by the word "continuous" I mean to cover a completely continuous 5 movement and discharge or an intermittent movement and discharge at desirable intervals. The period of nonuse of the furnace is done away with, and the operation is simple and easily carried out.

10 Many changes may be made in the form and arrangement of the apparatus, without departing from my invention.

I claim:

15 1. The method of producing silicon carbide, consisting in providing a charge of silicious and carbonaceous material in substantially reacting proportions, around a core of conducting resistance material continuously supplying current to the conduct- 20 ing resistance material, moving the resistance material and charge during the passage of the current, and supplying resistance material and charge material at one point in the movement and removing it at another 25 point in the movement.

2. The method of producing silicon carbide, consisting in providing a charge of silicious and carbonaceous material in substantially reacting proportions, around a 30 core of conducting resistance material passing electric current through the resistance core, supplying the charge material in contact with the core, moving the core and charge material during the operation, and

supplying and removing the materials in a substantially continuous manner.

3. The method of producing silicon carbide, which consists in providing a charge of silicious and carbonaceous material in substantially reacting proportions around a resistance core, supplying electric current to the core, moving the charge and core materials past the electrodes, and continuously supplying the core and charge material in one portion and removing them at another 45 portion.

4. The process of producing silicon carbide, which consists in providing a charge of silicious and carbonaceous material in substantially reacting proportions supplying a 50 core of conducting resistance material embedded in and inclosed by the charge of silicious and carbonaceous material, oppositely disposing and maintaining the electrode terminals in conductive relation with said core, passing electric current through said resistance material continuously moving said resistance material and charge with reference to said electrodes, continuously supplying charge and resistance material at 55 the first electrode and removing the finished product at the second electrode.

In testimony whereof, I have hereunto set my hand.

FRANK J. TONE.
